REFINING OF COKE-OVEN LIGHT OIL

Bernard J. C. van der Hoeven, Pittsburgh, Pa., and John Walker Unroe, Steubenville, Ohio, assignors, by mesne assignments, to Koppers Company, Inc., a corporation of Delaware

Application February 13, 1941, Serial No. 378,746

5 Claims. (Cl. 202—40)

The present invention relates in general to improvements in the refining of crude light oil that is volatilized into the gas stream evolved from coke ovens during the carbonization of coal and also in the recovery of refined products therefrom. The invention comprehends, more particularly, improvements in the production of benzene of so-called nitration grade with simultaneous recovery of other preferred and useful fractions of crude light oil.

An object of the present invention is the segregation of the components of crude light oil into new and useful fractions comprising relatively high concentrations of compounds of closely related physical characteristics.

Another object of the invention is improvement in the economics of separating benzene of so-called nitration grade from crude coke-oven light oil containing non-aromatics which boil at temperatures very near the boiling point of benzene, while producing only small amounts of distillation-intermediates.

Another object of the present invention relates in general to the economics of light-oil refining and specifically to the improved separation from crude light oil containing non-aromatics boiling at temperatures near the boiling point of benzene, of a partially refined fraction from which an improved yield of refined benzene, and especially of benzene of nitration grade, can be recovered with a single direct distillation step and without excessive production of intermediates.

A further object of the invention is to provide improvements in the refining of crude coke-oven light oil whereby the non-aromatic light oil constituents boiling just lower than the boiling point of benzene are removable in a fraction sufficiently low in sulphur content that it is utilizable as motor fuel.

A further object of the present invention is the attainment of the above-stated objects by continuous distillation steps in apparatus comprising only two fractionating columns.

The invention has for further objects such other improvements and such other operative advantages or results as may be found to obtain in the processes or apparatus hereinafter described or claimed.

The presence in crude light oil of non-aromatics which boil at temperatures very near the boiling point of pure benzene has heretofore required extensive treatment of said crude light oil and involved the production of considerable amounts of intermediate fractions in order to

produce benzene of nitration grade which by the Barrett manufacturing specifications for coke-oven light oil distillates, must solidify at a temperature not lower than 4.85° C.

5 According to the invention, crude light oil is preferably separated by a continuous fractional distillation into at least three fractions having distinct and preferred characteristics.

Of these fractions the lowest boiling fraction, 10 namely, the forerunners, is a relatively small portion of the original crude light oil and is substantially free of benzene and has a high concentration of the sulphur compounds present in the crude light oil. The lower-boiling constituents are partially condensed and the fixed gases 15 therein are returned to the coke-oven-gas stream for combustion therewith. The condensable forerunners are employed in part as reflux, the excess thereof being continuously removed to 20 preferred storage.

Another fraction of intermediate boiling range and low specific gravity, wherein non-aromatics are highly concentrated and which represents only a small percentage of the total treated light oil is also continuously removed during this fractional distillation. This product is sufficiently low in sulphur concentration to be utilizable as motor fuel or as a blend with same.

25 The remainder of the crude light oil from which has been removed the two previously described lower boiling fractions, constitutes a third fraction. From this fraction after acid washing, there can be fractionally distilled to produce benzene of so-called nitration grade not less than 30 substantially 90 per cent of the benzene originally present in the crude light oil. The bottoms-product from this second distillation can be batch-distilled to produce toluene, the xylenes, and light and heavy solvent naphtha.

40 The present invention thus provides for the production of nitration pure benzene in only two distillation steps. In the first of these steps the crude light oil is substantially stripped of those constituents boiling below benzene which heretofore have presented difficulties in their removal from the crude light oil without simultaneous removal of considerable benzene; and in addition the said constituents have been segregated into 45 novel fractions having significantly low specific gravities and other distinct characteristics whereby the said fractions, themselves, have individual utility. The removal of the said low boiling constituents is sufficiently extensive that nitration pure benzene is directly recoverable in 50 the second distillation step.

In the accompanying drawing forming a part of this specification and showing for purposes of exemplification a preferred apparatus and method in which the invention may be embodied and practiced but without limiting the claimed invention specifically to such illustrative instance or instances:

Fig. 1 is a diagrammatic elevational view of apparatus for distillation of crude light oil in accordance with the present invention;

Fig. 2 is a horizontal section on an enlarged scale taken along lines II-II of Fig. 1; and

Fig. 3 is a vertical cross section of a fragment of a fractionating column taken along lines III-III of Fig. 2.

The same characters of reference designate the same parts in each of the views of the drawings.

In Fig. 1 is shown diagrammatically a distillation system that makes possible the practical realization of the improvement provided by the present invention and which includes fractionating column 10, fractionating column 60, batch-still kettle 90, and batch-still rectifying column 100. The direction of travel of the light oil and of the fractions thereof through the system is indicated by arrows in the drawing.

Crude light oil is pumped continuously through feed line 11 into the fractionating column 10 at a point intermediate the top and bottom of said column. Fractionating column 10 that is about three feet in diameter and about ninety feet high comprises a shell 13 with a reboiler 14 and about forty bubble-cap trays 12 which are contained therein. A bubble-cap tray in some detail is shown in the enlarged scale Figures 2 and 3. The trays are disposed horizontally and mutually parallel, and each contains a plurality of vapor ports 16 which are covered by bubble caps 17. For clarity, the bubble caps in Fig. 3 are shown in slightly larger scale than those in Fig. 2. Adapted for the retention of a preferred depth of liquid on each tray are weir-plates 18, and adapted for directing the flow of liquid from a tray to the one immediately therebeneath are liquid by-passes 19 which are vapor sealed by liquid retained at their lower ends by seal plates 20. The light oil is received on an intermediate bubble-cap tray 12 of column 10 and is therein fractionally distilled by heat from reboiler 14, which is disposed at the bottom of the column, and the said heat of which selectively advances the lighter boiling constituents to the upper plates thereof.

The forerunnings-vapors issuing from the top of column 10 are conducted through vapor line 21 to condenser 22 wherein the vapors are cooled to approximately 20° C. and wherein a portion of the vapors are thereby condensed. The fixed gases therefrom are returned through vent line 23 to a fuel-gas stream and are eventually burned therein. The issuance of said gases from the system is controlled by an automatic vapor pressure controller 24 which maintains a slight positive pressure on the contents of said column 10. The maintenance of this positive pressure upon the boiling contents of the column by increasing the boiling temperature respectively of each tray advantageously prevents the rise of higher boiling fractions to the top trays of the column and insures the production of purer products than could be otherwise produced.

The condensed forerunnings are continuously withdrawn from condenser 22 and are run through drain line 25 to decanter 26 in which water which may have condensed with the forerunnings is separated therefrom. The fore-

runnings are thereafter continuously pumped from the decanter through reflux line 27 by pump 28 contained therein, and are continuously returned as reflux through said line to the top of column 10. The volume of the reflux is preferably about double the volume of feed to the column. A previously determined volume of fore-runnings can be regulably withdrawn through product line 29 to storage tank 30 by adjustment of valve 31.

A sidestream product is withdrawn from one or more of several therefor-adapted adjacently-disposed bubble-cap trays which are situated intermediate the feed-receiving tray and the top of the column. The volume of sidestream can be adjusted manually by operation of valves 32, and with the aid of flow meter 33 in sidestream product line 34 in which the sidestream is removed. The sidestream is cooled in water-fed indirect cooler 35 and is thereafter flowed through a continuation of line 34 to motor-benzol storage tank 36 that is adapted for the addition of motor-fuel inhibitor by connection with inhibitor storage tank 37.

From the bottom of the column 10 a partially refined light oil that is stripped of its lower boiling fractions is continuously withdrawn through drain line 39 at a rate governed by an automatic liquid-level controller 40 which operates a valve 41 in product line 42. The said partially refined light oil is cooled by indirect contact with water in cooler 43. This light oil fraction is stored in storage tank 45 whence it is pumped through line 47 to agitator 50 by pump 48 that is included in said line 47. The oil is acid washed in the agitator, is neutralized by an alkali wash in alkali wash tank 51 and, thereafter, the acid-washed fraction thus neutralized is withdrawn to treated-oil storage tank 52.

This treated product is withdrawn preferably continuously from said storage tank 52 by pump 53, is pumped through feed line 54 to a fractionating column 60 and is received on one bubble-cap tray of a plurality of superposed trays 62 forming the said fractionating column. The so-fed light oil flows downwardly toward a reboiler 64 at the base of the column and is fractionally distilled by the heat of said reboiler in a manner that is similar to that obtaining in column 10 and that is well known to the art.

The vapors leaving column 60 are conducted through vapor line 65 to condenser 66 in which they are condensed by indirect contact with cooling water. The condensed overhead fraction is flowed from condenser 66 through pipe line 68 to decanter 70 in which water can be separated from the condensed fraction. The pure product is decanted therefrom and flowed through drain line 71 from which a portion of the product is pumped by pump 74 through reflux line 72 to the top of column 60 down through which the said portion is refluxed. The remainder of the product is drained through product line 73 to nitration-benzene storage tank 75.

From the base of said column 60 a bottoms-product is withdrawn through drain line 76 at a rate that is governed by an automatic liquid-level controller 80 which operates a valve 81 in said line. The product is flowed through cooler 82 that is disposed in drain line 76 and into batch-feed storage tank 85. This bottoms-product is pumped therefrom through batch-feed line 87 by pump 88 to batch-still kettle 90 whenever the operation of the batch-still requires a recharging

of said kettle. The oil within the kettle is heated by steam coils 91 and its volatilized vapors flow through vapor line 92 to the base of batch-still rectifying column 100, wherein is intermittently produced as overhead product further amounts of the benzene residual to the first two fractionation steps and, in succession, the higher-boiling heavier fractions of light oil such as, for example, toluene, xylenes, and light and heavy solvent naphtha. Condensate drained from fractionating column 100 is returned to kettle 90 through return line 93. The still residue from this batch distillation is discharged from the kettle through drain line 94.

The vapors flow from the top of column 100 through vapor line 101 to a vapor neutralizer 102 wherein the vapors are washed by a caustic soda solution to remove any corrosive constituents therefrom. Thereafter, the neutralized vapors flow through neutralized vapor line 104 to a condenser 105 wherein they are condensed. The thus-condensed product drains through drain-line 106 and is separated from therewith-condensed water in decanter 107. Caustic soda solution with entrained light oil is drained from the neutralizer through pipe line 103 to decanter 107a wherein the said solution and said entrained light oil are separated. The entrained soda solution and the water are drained from decanters 107a and 107, respectively, through drain lines 108 and are collected in caustic soda pump-tank 110. The soda solution is returned through caustic soda line 112 to the vapor neutralizer by soda circulation pump 111. The neutralized and so-separated product is flowed through pipe line 109 and a portion of same is pumped by reflux pump 120 through line 121 to the top of the rectifying column 100 wherein it is employed as reflux. The remainder is delivered by pipe line 113 to one of several pure-products receiver tanks 114. The said receiver tanks 114 are provided with a manifold 115 by which said separated products can be individually distributed to selected storage. Pipe-line 116 is disposed to convey benzene separated by the batch still from said manifold to motor-fuel storage tank 36.

In the operation of apparatus illustrated in the drawing to obtain benefits provided by the present improved method, crude light oil is preferably flowed into column 10 at a rate of about 300 to 350 gallons per hour.

Crude light oil is continuously fractionated in fractionating column 10 as is hereinabove described. An adequate amount of heat is supplied to the reboiler 14 to drive continuously from the top of the column those components of the crude light oil having the lowest boiling points. These vapors are partially condensed in condenser 22 and are cooled therein to about 20° C. The most highly volatile compounds that, in one example, comprised about two per cent of the original crude light oil, are returned to the coke-oven-gas stream, thereby to be utilized as added heat value. The vapors are substantially free of benzene and comprise highly volatile light-oil components having a substantial proportion of the sulphur compounds of the original crude light oil. Undesirable sulphur-bearing constituents are thereby advantageously removed from the oil in relatively concentrated form. The condensed forerunnings from the condenser are returned at a rate of about 550 to 600 gallons per hour through pipe line 27 to the top of the tower and are employed therein as reflux. As the condensable forerunnings ac-

cumulate, they are withdrawn through pipe line 29 to forerunnings-storage tank 30. Certain compounds, such, for example, as carbon bisulphide, which are of advantageously high concentration in the forerunnings, can be obtained therefrom.

From any one or from several of adjacent trays near the top of column 10 not more than about 2.5 per cent of the volume of the inflowing light oil is removed as a sidestream having a 10 rather high concentration of non-aromatic constituents. This sidestream is taken from such preferred trays and at a rate such that it contains: a high concentration of the non-aromatics boiling just below benzene, not more than about two per cent of the benzene present in the original crude light oil and a sufficiently low concentration of sulphur to make said sidestream product available for, or for blending with, motor fuel. The preferred tray or trays employed are usually characterized by their containing thereon a liquid fraction having a specific gravity lower than that on the superposed trays or on those immediately therebeneath. The specific gravity of the sidestream product is always below that of pure benzene and has been found to vary from 0.79 to 0.83. These values for specific gravity of the sidestream are low in consequence of the low specific gravity of the non-aromatics that, as is above mentioned, are present in relatively high 20 concentration therein.

Determinations by standard tests show, for example, that the paraffinic content alone varies from 12 to 26 per cent of the total sidestream and the total sulphur content has been as low as 35 0.17 per cent and as much as 0.33 per cent of the total. In addition to its content of paraffins the non-aromatics of the sidestream also comprise a significant amount of unsaturated compounds. These unsaturates are thus removed in a low-sulphur fraction thereby making the same utilizable as motor fuel, whereas the said unsaturates would otherwise be removed with the forerunnings and consequently would be unavailable therefor, or they would be changed to an un-40 available form during the acid-washing step.

From the bottom of column 10 is continuously withdrawn a product which contains not less than substantially 95 per cent of the benzene originally in the crude light oil, and substantially 50 none of the compounds boiling below benzene. This product is then acid washed to produce a treated light-oil fraction that can be directly distilled to separate a high yield of nitration pure benzene; it requires less acid for its washing than 55 would be usually required after a single continuous fractionation because of the substantially complete removal in the sidestream of compounds boiling lower than and near the boiling temperature of benzene. After removal of the acid sludge 60 the acid-treated product is further treated with an alkali to neutralize it.

In the second fractionating column 68, this latter acid- and alkali-treated fraction is continuously distilled, and not less than substantially 65 ninety per cent of the benzene originally contained in the light oil is volatilized, condensed and thus recovered as nitration pure benzene having a solidification point of at least 4.85° C. The solidification point of the benzene can be increased by increasing the volume of the non-aromatics-containing sidestream product, and thereby nitration benzene having solidification 70 temperatures of, for example, 5.3° C. and higher has been economically produced.

The product effluent of the bottom of the col-

umn 60 contains a small amount of benzene and substantially all of the compounds of the crude light oil that boil above the boiling point of benzene; it is continuously withdrawn and stored in batch-feed storage tank 85 from which it is intermittently charged to batch-still kettle 90. The batch still is disposed for operation in combination with the two continuous fractionating columns of the system and adds desirable flexibility to the distillation operation in that large quantities of the said bottoms-product can be stored in batch-feed storage tank 85 and in the still kettle 90 itself and can thereafter be distilled at will.

The small amount of benzene remaining in the said product effluent to column 60 is distilled in the batch still and returned through product line 116 to the motor-fuel storage tank 36. The higher boiling fractions of crude light oil such as, for example, toluene, the xylenes, and light and heavy solvent naphtha are successively removed by fractionation from the said product as overhead vapors which are thereafter neutralized and condensed, a portion of the liquid products therefrom being employed as reflux whereas the remainder is stored for future distribution.

From the above-given description it is apparent that, according to the present invention and by the use of only two fractionating columns, from crude light oil there can be separated nitration benzene comprising not less than substantially ninety per cent of the originally therein present benzene, and having a solidification point of not less than 4.85° C. In addition, the highly complex mixture of constituents of the original crude light oil that boil below benzene is separated simultaneously into the following fractions: the one fraction comprising permanent gases and very low boiling constituents which are returned to the gas stream to be burned; another fraction wherein sulphur-bearing constituents, such as carbon bisulphide, are of such high concentrations that the said fraction is useful as a raw material from which valuable products are obtained; and another fraction of low specific gravity wherein non-aromatics are highly concentrated and that contains unsaturates which are especially valuable for their anti-knock properties in motor fuels, the said latter fraction being sufficiently low in sulphur-bearing constituents to make it suitable directly for this purpose. That benzene which is not recovered as nitration pure benzene is removed from the crude light oil as a product which is suitable for use as a motor fuel. The higher boiling homologues of benzene, such as toluene, the xylenes and solvent naphtha are also obtained in extremely pure form.

The invention as hereinbefore set forth is embodied in particular form and manner but may be variously embodied within the scope of the claims hereinafter made.

We claim:

1. In a process for the refining of crude light oil that is obtained from coke-oven gas, the steps of: continuously flowing non-acid washed crude light oil aforesaid into a fractionating column; boiling said light oil therein and simultaneously treating evolved vapors with a reflux of fore-runnings' constituents of said light oil having a boiling point lower than benzene at a rate, by volume, at least about one and one-half times the rate, by volume, at which said crude light oil is flowed into said fractionating column and thereby separating said crude light oil into a plu-

rality of fractions comprising a low-boiling fore-runnings fraction that is substantially free of benzene, another fraction containing some benzene and a relatively high concentration of non-aromatic light-oil constituents having boiling points lower than but more closely adjacent the boiling point of benzene than the constituents of the first said fraction, said other fraction having a specific gravity of from 0.79 to 0.83, and a distillation residuum containing at least substantially ninety-five per cent of the benzene originally present in the light oil, said residuum being free of fore-runnings and non-aromatic hydrocarbon constituents of light oil having boiling points less than benzene; recovering the plurality of said fractions; and acid-washing said residuum and fractionally distilling therefrom without substantial production of lower boiling intermediates, about ninety per cent of the total originally contained benzene of said light oil as a product having a solidifying point of at least 4.85° C.

2. In a process for the refining of crude light oil that is obtained from coke-oven gas, the steps of: continuously flowing non-acid washed crude light oil aforesaid into a fractionating column; boiling said light oil therein and simultaneously treating evolved vapors with a reflux of fore-runnings' constituents of said light oil having a boiling point lower than benzene at a rate, by volume, at least one and one-half the rate, by volume, at which said crude light oil is flowed into said fractionating column and thereby separating said crude light oil into a plurality of fractions comprising, a low-boiling fore-runnings fraction that is substantially free of benzene, another fraction containing some benzene and a relatively high concentration of non-aromatic light oil constituents having boiling points lower than but more closely adjacent the boiling point of benzene than the constituents of the first said fraction, said other fraction having a specific gravity of from about 0.79 to 0.83, and a distillation residuum containing at least substantially ninety-five per cent of the benzene originally present in the light oil, said residuum being substantially free of fore-runnings and non-aromatic hydrocarbon constituents of light oil having a boiling point less than benzene; and recovering the plurality of said fractions.

3. In a process for the refining of crude light oil that is obtained from coke-oven gas, the steps of: flowing non-acid washed crude light oil aforesaid into a fractionating column; boiling said light oil therein while treating the evolved vapors with a reflux of fore-runnings' constituents of said light oil having a boiling point lower than benzene at a rate, by volume, at least one and one-half the rate, by volume, at which said crude light oil is flowed into said fractionating column and thereby segregating in a portion of said column a liquid light-oil fraction containing non-aromatic hydrocarbon constituents of said light oil that boil at a higher temperature than said fore-runnings' constituents and boil closely adjacent to but below the boiling point of pure benzene, said liquid fraction having a specific gravity of between about 0.79 and 0.83; and recovering said liquid fraction from said fractionating column substantially independently of other fractions separated therein from said light oil.

4. In a process for the preparation of highly refined benzene from non-acid washed crude coke-oven light oil containing also a non-aromatic hydrocarbon of which the boiling point is

closely adjacent to but below that of pure benzene, the steps of: in a fractionating column, refluxing vapors, derived by boiling said non-acid washed crude light oil in fractionating apparatus, with a flow of liquid constituents that have been previously derived from said crude light oil and that boil below both benzene and said non-aromatic hydrocarbon, at a rate, by volume, about double the rate by volume, of flow of crude light oil into said fractionating apparatus, and thereby segregating in said fractionating column a liquid mixture containing said non-aromatic hydrocarbon and having a specific gravity of between 0.79 and 0.83; and recovering said liquid fraction from said fractionating column substantially independently of higher boiling constituents of said crude light oil.

5. In a process for the preparation of highly-refined benzene from non-acid washed crude coke-oven light oil containing also a non-aro-

matic hydrocarbon of which the boiling point is closely adjacent to but below that of pure benzene, the steps of: in a fractionating column, refluxing vapors, derived by boiling said non-acid washed crude light oil in fractionating apparatus, with a flow of liquid constituents that have been previously derived from said crude light oil and that boil below both benzene and said non-aromatic hydrocarbon, at such a rate, by volume, larger than the rate by volume, of flow of crude light oil into said fractionating apparatus, as to thereby segregate in said fractionating column a liquid mixture containing said non-aromatic hydrocarbon and having a specific gravity of between 0.79 and 0.83; and recovering said liquid fraction from said fractionating column substantially independently of higher boiling constituents of said crude light oil.
